UNITED STATES PATENT OFFICE.

PAUL K. WOOD, OF ELYRIA, OHIO, ASSIGNOR TO THE GARFORD MANUFACTURING COMPANY, OF ELYRIA, OHIO, A CORPORATION OF OHIO.

AUTOMOBILE-HORN.

1,200,680.

Specification of Letters Patent.

Patented Oct. 10, 1916.

Application filed April 1, 1915. Serial No. 18,428.

To all whom it may concern:

Be it known that I, PAUL K. Wood, a citizen of the United States, residing at Elyria, in the county of Lorain and State of Ohio, have invented certain new and useful Improvements in Automobile-Horns; and I do hereby declare the following to be a full, clear, and exact description of the invention, such as will enable others skilled in the art 10 to which it appertains to make and use the same.

This invention relates to signaling devices which have a variety of uses, but which are more particularly intended to be employed upon automobiles, motor cycles, motor boats and other vehicles, where it is desired to give a warning of the presence or approach of the vehicle. More particularly, I aim to improve the horn illustrated and 20 described in the patent to Ray H. Manson, No. 1,110,989, Sept. 15, 1914. Both inventions relate to the types of horns known as vibrator horns, which are already in extensive and successful commercial use.

25 One of the objects of my invention is to produce a cheap, conveniently made and compact structure, and at the same time, an efficient horn which operates upon a reasonable voltage and with a reasonable current 30 to produce the desired signal.

With the increase in amount and complexity of the machinery employed under the hood of an automobile, where the horns are generally mounted in present day usage, it 35 is highly desirable that the horn should occupy as little space as possible, in order that it shall not interfere with the repair, adjustment and care of the other machinery with which it is associated. With the introduction of the electric horn in use upon 40 motor cycles, it is necessary that the horn should occupy but little space and should extend but little ways behind the handle bars.

45 The object of the present invention is to produce what is familiarly known as a small horn, which occupies but little space, especially in a longitudinal direction, and which at the same time can produce such a 50 signal as is required. As the diaphragm, made to produce the desired signal, must possess considerable area, it is difficult, if not impossible, to limit the size of the horn except by reducing its length, which I have

done, and which enables me to realize the advantages sought by me. 55

Other objects of my invention and the invention itself will be better understood from a description of an embodiment thereof.

Figure 1 is a sectional view through an 60 embodiment of my invention showing part of the resonator in elevation. Fig. 2 is a rear elevation with the cover removed. Fig. 3 is a section through the armature and associated contacts. 65

Referring now to the drawing and to the embodiment of the invention illustrated therein, at 4 is shown a flat frame piece, which here consists of a ring of metal which is provided with a large central opening 5, 70 for a purpose to be described. A vibratile, sound producing diaphragm 6 is mounted in front of this frame piece and preferably connected thereto around its periphery, leaving the central part of the diaphragm exposed through the opening 5 and free to vibrate in one direction in said opening. A ring 7 of cork or other suitable material is preferably placed in front of the diaphragm. In front of the ring of cork the casing front 80 8 is mounted, and the parts 4, 6, 7 and 8 are connected together by any suitable means, such as screws 9, which serve to clamp the periphery of the diaphragm between the members 4 and 7. The central portion of the 85 front 8 is struck outward, as shown at 10 to form a chamber 11 in front of the diaphragm to permit it to vibrate freely in a forward direction. The outer edges of the casing 8 are turned backward as shown at 11. An 90 opening 12 is provided in the center of the casing front for the egress of the sound waves. A resonator 13 may be mounted in this opening, if desired, and may be connected thereto by forming a collar 14 around 95 the edges of the opening 12 and connecting the resonator thereto, as shown in Fig. 1.

Electromagnetic means are provided for 100 vibrating the diaphragm, which are here shown as an electromagnet 15 and an armature 16. The magnet consists of a winding 17 which is preferably made elliptical in cross section, the long axis of the ellipse being parallel to the diaphragm. A single pole piece, core or polar extension 19 is provided, and the winding is mounted thereon. The pole piece is connected to the frame piece 4 at one end by suitable means, such 105

as screws 20. The end 21 of the pole piece, which is connected to the frame, is broadened by providing thereon extensions 22, and the screws 20 are inserted through these 5 extensions in order not to reduce the magnetic circuit where the holes are formed for the screws.

The magnet may be spaced from the frame piece by providing a spacing member 10 24 between the end 21 of the core and frame piece. When mounted, one edge 25 of the magnet is within the hole 5 in the frame piece 4. The armature 16 is supported through an intermediate member 30 and a 15 flat spring 31 from the frame piece 4. A hammer is operated by the armature, here shown as an extension 32 of the member 30, this extension being turned downward to form the hammer, which will strike the 20 diaphragm and vibrate the same when the armature is operated. The members 31 and 30 are connected together by any suitable means, such as rivets 34. An electric switch is shown at 40 consisting of contacts 41 and 25 42. The contact 41 consists of an adjustable screw whose head is shown at 44 mounted in a bracket 45 connected to the frame piece by any suitable means, such as screws 46, preferably also employed to connect the 30 spring 31 to the frame piece 4. The second contact 42 is supported by a contact spring 50, which is connected to one end of the bracket 45, the spring 50 extending the 35 length of this bracket substantially perpendicular to the long axis of the magnet.

The spring 50 is operated by the armature through a stud 51. When thus mounted the center of the armature is a little to one side of the center of the pole piece 19, but 40 in front of the magnet, as shown in Fig. 1. The two, however, are out of alinement with respect to the diaphragm, so that the armature swings in a path which clears the magnet, no matter how far it is extended. When 45 the magnet is energized, the armature 16 is drawn down toward the pole piece 19, and the hammer 32 strikes the central portion of the diaphragm, causing it to vibrate and produce the signal. When the armature 16 is drawn down, the stud 51 is removed from the spring 50, which is normally stressed to 50 follow the stud, and in following it, opens the switch which interrupts the circuit of the magnet, which releases the armature, 55 whereupon the parts are restored to normal. This operation continues as long as the circuit is closed by the switch, which is not shown, but which is understood.

I claim:

60 1. In an automobile horn, the combination of a frame piece, a diaphragm associated therewith, an electromagnet supported from the frame piece substantially parallel to the diaphragm and with its operating end adjacent the central portion of the diaphragm,

said electromagnet consisting of a single pole piece and a winding thereon, an armature controlled by the electromagnet for actuating the diaphragm, said armature being normally positioned in front of the magnet 70 and with its center to one side of the center of the core thereof, said armature when attracted by the electromagnet moving substantially perpendicular to the long axis of the magnet, means supported from the 75 frame for supporting and positioning the armature to move in a path clearing the front of the electromagnet and an electric switch controlled by the armature.

2. In an automobile horn, the combination of a flat frame piece having a large opening in the central portion thereof, a diaphragm, means to connect the diaphragm to said frame piece with the central portion of the diaphragm extending over said opening, the central portion of said diaphragm being adapted to vibrate in one direction into and out of the opening in the frame piece, an electromagnet consisting of a single polar extension and a winding thereon connected to the back part of the frame piece with the free end of the magnet adjacent one end of the armature and means to connect the other end of the magnet to the frame piece with a portion of the magnet 90 in the opening in the frame piece, an armature for said magnet and means including a flat spring for connecting said armature to the frame piece, said armature being normally positioned in front of the magnet, 95 a hammer carried by the armature for striking the diaphragm when the same is vibrated, and an electric switch controlled by the armature.

3. In an automobile horn, the combination of a flat frame piece having a large opening in the central portion thereof, a diaphragm connected to the front of the frame piece at its periphery and extending over the opening in the frame piece, a single 105 magnet core connected at one end to the back side of the frame piece and having its free end extending substantially parallel to the diaphragm to a point adjacent the center thereof, a flat magnet winding on 110 said core, an armature for said magnet normally in front of the magnet, the center of the armature being to one side of the center of the magnet core, said armature when attracted by the magnet swinging in a 115 path substantially perpendicular to the long axis of the magnet and clearing the front of said magnet, means including a leaf spring by which the armature is connected to the frame piece and an electric switch 120 controlled by the armature.

4. In an automobile horn, the combination of a flat frame piece having an opening in the central portion thereof, a diaphragm connected to the front of the frame 125

- piece at its periphery and extending over the opening in the frame piece, the central portion of the diaphragm swinging into and out of the opening in the frame piece
- 5 when the diaphragm is vibrated, means to connect the diaphragm to the front of the frame piece, means to operate the diaphragm including an electromagnet, said electromagnet consisting of a single flat
- 10 core, means to connect one end of the core to the back side of the flat frame piece, the core of the magnet extending substantially parallel to the diaphragm over the opening in the frame piece with its free or armature
- 15 actuating end adjacent the central portion of the diaphragm, a flat magnet coil on said core with a portion of the magnet winding in the opening in the frame piece, both the magnet winding and the core being
- 20 mounted with their two longest axes parallel to the diaphragm, an armature for said magnet, means including a flat leaf spring to connect the armature to the back of the frame piece, said means holding said
- 25 armature normally in front of the magnet with the center of the armature to one side of the pole piece, a hammer carried by said armature for striking and vibrating the diaphragm when the armature is actuated,
- 30 said armature when actuated swinging in front of the magnet and in a line substantially perpendicular to the long axis of the magnet and an electric switch supported from the back side of the frame piece controlled by said magnet.
5. In an automobile horn, the combination of a flat frame piece having its central portion cut away to form a large opening in the central portion of the frame piece,
- 40 said opening being concentric with the outer periphery of the frame piece, a vibratile, sonorous diaphragm connected at its periphery to the front side of the frame piece and having its central portion extending
- 45 over the opening in the frame piece, a casing front in front of the diaphragm associated with the diaphragm about its periphery, means to connect the frame piece, the diaphragm and the casing front together,
- 50 the central portion of the casing front being struck outward to form a chamber into which the central portion of the diaphragm vibrates in its forward movement, the central portion of the diaphragm swinging
- 55 into and out of the opening in the frame piece upon its rearward movement when vibrated, mechanism to operate the diaphragm including an electromagnet and an armature, said electromagnet consisting of a single flat pole piece, means to connect one end of the pole piece to the back side of the frame piece with the pole piece extending over the opening in the frame piece with the free end of the pole piece near the center of
- 60 the diaphragm, the two longest axes of said
- pole piece being parallel to the diaphragm, and a flattened magnet winding on said pole piece with its two longest axes parallel to the diaphragm, means to connect the armature to the back side of the frame piece including a flat leaf spring, said last named means holding the armature normally in front of the magnet and in such a position that the center of the armature is to one side of the center of the magnet, a hammer
- 70 carried by the armature for striking the diaphragm and causing it to vibrate when the armature is vibrated, a bracket connected to the back side of the frame piece, and an electric switch carried by said bracket consisting of a pair of contacts, one of which is controlled by the armature, said switch controlling the circuit of the magnet and being opened when the armature is attracted and closed when the armature is released.
6. In an automobile horn, the combination of a flat frame piece provided with an opening in the center thereof, a diaphragm connected to the frame piece and extending over the opening therein, the rear of the diaphragm being exposed through said opening, means for actuating the diaphragm consisting of a magnet and a vibratile armature, the magnet consisting of a single pole
- 75 piece connected at one end to the frame piece and extending substantially parallel to the diaphragm over the opening in the frame piece with its free or armature actuating ends adjacent the central portion of the diaphragm and a flattened magnet winding on said pole piece, means to connect the armature to the back side of the frame piece including a flat leaf spring, said armature being held in front of the magnet and when actuated by the magnet moving substantially perpendicular to the long axis of the magnet in a path clearing the front of the magnet, and an electric switch controlled
- 80 by the armature.
7. In an automobile horn, the combination of a flat frame piece, a diaphragm associated therewith, an electromagnet supported from the frame piece substantially parallel to the diaphragm and with its operating end adjacent the central portion of the diaphragm, said electromagnet consisting of a single pole piece and a winding thereon, an armature controlled by the electromagnet for actuating the diaphragm, said armature being
- 85 normally positioned in front of the magnet and when attracted by the electromagnet moving substantially perpendicularly to the long axis of the magnet to cause the actuation of the diaphragm, means supported from the frame for supporting and positioning the armature to move in a path clearing the front of the electromagnet and an electric switch controlled by the armature.
8. In an automobile horn, the combination

- of a flat frame piece, a vibratile sonorous diaphragm connected to the front of the frame piece, an electromagnet and an armature connected to the rear of the frame piece, said electromagnet consisting of a single pole piece and a magnet winding thereon, means to connect one end of the pole piece to the back of the frame piece with the winding and pole piece extending substantially parallel to the diaphragm and with the free or armature actuating end of the magnet adjacent the central portion of the diaphragm, means to connect the armature

ture to the back of the frame piece, mechanical means through which the armature actuates the diaphragm when the armature is vibrated and an electric switch controlled by the armature. 15

In testimony whereof, I have affixed my signature in the presence of two witnesses; 20 this 26th day of March, 1915.

PAUL K. WOOD.
